UNITED STATES PATENT OFFICE.

HOWARD J. GIRSHEFSKI AND ADDISON B. KNOTTS, OF RAMOS, LOUISIANA.

LIQUID-DISPENSING APPARATUS.

1,188,267.

Specification of Letters Patent. Patented June 20, 1916.

Application filed August 18, 1915. Serial No. 46,153.

To all whom it may concern:

Be it known that we, HOWARD J. GIRSHEFSKI and ADDISON B. KNOTTS, residing at Ramos, in the parish of St. Mary and State 5 of Louisiana, have invented certain new and useful Improvements in Liquid-Dispensing Apparatus, of which the following is a specification.

This invention has reference to means provided for the withdrawal of liquids of different specific gravity contained within a tank or other like receptacle and it primarily has for its object to provide an improved means of the general character stated of a simple 10 and economical construction, more especially designed for draining off liquids, such as syrups, brine, etc., in which the use of valved outlets are dispensed with, and in which the several parts are co-operatively so arranged 15 that the drain tube or passage may be readily set within the fluid holder for draining the contents thereof, either from the top or bottom.

Another object of our invention is to provide a dispensing means of the general character stated that includes devices operated from the outside of the tank for setting the draining pipe or tube at the desired draining position and for holding it to such positions, 20 other means being also included for automatically closing off the inlet to the said tube when it is turned to its inoperative position whereby to keep the liquid within the tank from splashing into the upper end thereof 25 when the said tank or holder is in transit.

With these and other objects in view the invention consists in the peculiar construction and novel arrangement of parts herein-after fully explained, specifically pointed 30 out in the appended claims and illustrated in the accompanying drawings, in which:—

Figure 1 is a vertical longitudinal section of our improved liquid dispensing means, the drawing off tube or pipe being shown 35 positioned for drawing off the liquid at the top of the said tank. Fig. 2 is a similar view of a part of said tank that shows the said tube or pipe lowered for completely draining off the bottom of the tank. Fig. 3 40 is a detail longitudinal section of the tank, the draining pipe being shown at its vertical or inoperative position with its attached closure device in engagement with the top of the tank. Fig. 4 is a detail view of the 45 upper end of the said pipe with the attached closure device in the open position. Fig. 5

is a transverse section of the tank and the dispensing means taken substantially on the line 5—5 of Fig. 1. Fig. 6 is a side elevation of one end of the tank and illustrates 60 the bracket bearing for the outlet pipe and the lever device for rocking the said pipe in the said bearings. Fig. 7 is a detail view of the tooth rack showing its connection to the brace member.

In the drawings, in which like numerals indicate like parts in all of the figures, 1 designates the liquid holder, which may be a tank, as shown, or a stationary trough or reservoir. The holder 1, at one end thereof, 70 has a pendent semi-circular or trough-like draining portion 10, which extends along the tank bottom a distance somewhat longer than the length of the draining off pipe or tube 3, the reason for which will presently 75 appear.

The pipe or tube 3 is in the nature of an elbow portion of the outflow pipe 30 that is rockably mounted in a lateral extension 31 secured to the tank and provided with a 80 stuffing box 32 that is arranged in the manner clearly shown in Fig. 6, by reference to which it will be noticed that the outer end of the pipe 30 is mounted in the brackets 4—4^a attached to the side of the tank and 85 which unite to form a bearing 40 for the said pipe 30 and which is braced by the collar 5 held in place on the pipe 30 by set screw 5^a, as shown.

6 designates a lever that is clamped upon 90 the pipe 30 and has the usual spring pawl device 60 for engaging with a segment rack 7 secured on one of the bracket members, the upper end of the lever when the elbow section of the pipe is at the vertical or inoperative position, lines up with an apertured ear 41 on the bracket member 4^a and is locked to the said ear by a pin 8 which passes through the ear and an aperture 61 in the lever, as shown. By reason of the peculiar constructions of the bottom of the fluid holder and the draining off pipe and the manner in which the said pipe is mounted I have provided a very simple and inexpensive means for emptying the holder or 100 tank and for positively draining off all of the contents thereof, it being readily understood, from the drawing, by pulling the lever 6 in the direction of the arrow α , Fig. 6, the tube or pipe 3, may be positioned at 105 any point within the tank for draining off the liquid, as desired, it being also apparent 110

that should the tank contain liquids of different specific gravity, say, oil and water,—the pipe 3 can be set to drain off either of the said fluids.

5 The elbow section 3 of the pipe 30 is provided with a closure device that is automatically held open when the said pipe 30 is draining out the contents within the tank and which closes the said section 3 when 10 such section is swung to the vertical position as shown in Fig. 1. The said closure device, which is illustrated in detail in Fig. 3, consists of a cap valve 2 hinged on a bracket 21 which extends laterally from the member 3 and the said cap valve is normally held to its open position by a pull spring 22 that connects to the bracket and to the heel 15 end 23 of the valve.

24 denotes a yielding contact member that 20 extends over the cap valve and which takes up the shock when the pipe section 3 is turned to the vertical position and the cap valve closes the upper end thereof.

By reason of mounting the dispensing 25 tank 30, as shown and described, danger of leakage around the pipe is overcome, and since the tube or elbow section 3 of the pipe 30 is of sufficient length to extend above the top of the liquid in the tank, when at the 30 vertical or inoperative position, and providing the upper end of the said tube with a closure device that is brought into contact with the top of the tank and thereby caused to seat onto the top of the pipe 3 and form 35 a closure therefor positively prevents the liquid within the tank from splashing into the tube 3, the said closure means for the tube or pipe 3 being especially advantageous in railroad tanks when the latter are in motion. By forming the bottom of the tank 40 with an elongated pendent trough as stated, the drawing off tube or pipe 3 can be lowered with its inlet end in a plane below the normal bottom line of the tank, as is shown 45 in Fig. 2.

From the foregoing description, taken in connection with the accompanying drawings, it is thought the complete construction, manner of operation, and the advantages of our 50 invention will be readily apparent to those skilled in the art to which the invention relates.

What we claim is:

1. A liquid dispenser comprising a tank 55 having a pendent longitudinally extended trough in the bottom thereof, and a tubular portion that extends laterally from the said trough, a drawing off pipe rockably mounted fluid tight in the said tubular extension, 60 means engaging the outer end of the drawing off pipe for turning it in its bearings,

the said drawing off pipe including an elbow portion within the tank that forms a draining tube, the said tube being of such length as to extend beyond the high level of the liquid within the tank when swung up to the vertical or inoperative position.

2. A liquid dispenser comprising a tank having a pendent longitudinally extended trough in the bottom thereof, and a tubular portion that extends laterally from the said trough, a drawing off pipe rockably mounted fluid-tight in the said tubular extension, means engaging the outer end of the drawing off pipe for turning it in its bearings, 75 the said drawing off pipe including an elbow portion within the tank that forms a draining tube, the said tube being adapted for lengthwise seating in the longitudinal trough in the bottom of the tank with its 80 inlet end below the normal bottom line of the tank.

3. A liquid dispenser comprising a tank having a pendent longitudinally extended trough in the bottom thereof, and a tubular portion that extends laterally from the said trough, a drawing off pipe rockably mounted fluid-tight in the said tubular extension, means engaging the outer end of the drawing off pipe for turning it in its bearings, 85 the said drawing off pipe including an elbow portion within the tank that forms a draining tube, the said tube being of such length as to extend beyond the high level of the liquid within the tank when swung 95 up to the vertical or inoperative position, and a closure device mounted on the upper end of the said tube normally open and adapted to engage with the top of the tank to be thereby moved to its tube closing position when the said tube is at the vertical 100 or inoperative position.

4. In a liquid dispensing apparatus, the combination of a liquid container having a pendent elongated trough in the bottom 105 thereof, and a tubular portion that extends laterally from the trough, a draining off pipe rockably mounted in the said tubular portion and held fluid-tight therein, said pipe including an elbow extension within 110 the container, brackets on the container that form a bearing for the said pipe, a lever attached to the pipe for turning it to bring the elbow portion at different angles in the container above the normal high level of the 115 liquid in the container to a horizontal position flatwise in the elongated trough in the bottom of the container, and means for locking the lever to its different adjusted positions.

HOWARD J. GIRSHEFSKI.
